(57) **CLAIM**

The ornamental design for an ultrasound device as shown and described.

DESCRIPTION

FIG. 1 is a rear perspective view of an ultrasound device showing the new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a rear view thereof in a state in which a handle is closed;

FIG. 9 is a left side view thereof in a state in which a handle is closed;

FIG. 10 is a right side view thereof in a state in which a handle is closed;

FIG. 11 is a top view thereof in a state in which a handle is closed; and,

FIG. 12 is a bottom view thereof in a state in which a handle is closed.

The broken lines in the drawings illustrate portions of the ultrasound device that form no part of the claimed design. The present article is an ultrasound device, and a handle is attached to a rear surface at the bottom side of the main body. The handle can be moved between a position where the handle protruding outward from the rear side is open, and a position as shown in each views in a state in which a handle is closed (a position along the bottom surface).
